UNITED STATES PATENT OFFICE

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA.

APPARATUS FOR TREATING OIL

Application filed September 1, 1920, Serial No. 407,405. Renewed October 15, 1926.

This invention relates to improvements in a process and apparatus for treating oil and refers more particularly to a process and apparatus adapted for the use in simultaneous cracking and dehydration of emulsified petroleum oils at atmospheric pressure.

The object of the invention is to provide a novel process and form of apparatus in which the oil may be dehydrated and distilled by surface distillation and in which the vapors may be superheated to a cracking temperature at atmospheric pressure while at the same time rotating the stills to insure a more effective distillation and prevent local overheating of the apparatus itself.

In the drawings, Fig. 1 is a view partly in side elevation and partly in vertical section of our improved apparatus. Fig. 2 is a similar view of the still member proper on an enlarged scale.

Referring to the drawings, 1 designates the firebox provided with a stack, 2. In this firebox is mounted a double still member consisting of a lower shell, 3, and an upper shell, 4. The shell member, 3, is provided at either end with a circumferentially extending gear, 5, supported on a trunnion, 6, carried by a standard, 7. At one end the shell member, 3, is provided with a driving shaft, 8, and driving pulley, 9, connected to any suitable source of power (not shown). The upper still shell member, 4, is provided at either end with a circumferentially extending gear, 10, which meshes by means of intermediate gear, 11, with the corresponding gear member, 5. The arrangement is such that the shell members, 3 and 4, are rotated in the same direction. It is to be understood that the shell members are supported in suitable guides (not shown) to prevent lateral displacement. Each shell member is open at one end to connect with a cap portion or stationary shell member, 12, and the rotating parts of the still are connected to the stationary parts through the ground joints, 13, or other suitable rotatable connections. The oil to be treated is charged by means of pump, 14, and line, 15, to the stationary part, 12, of the lower shell member, 3. Each of the stationary parts, 12, is provided with a residue drawoff, 16, con-

trolled by valve, 17. The vapors generated in the lower shell member, 3, pass to the upper shell member, 4, by means of the pipe connection, 18, connected to the stationary members, 12, and preferably provided with an extension, 19, projecting into the body of the upper rotating member, 4.

The vapors pass out of the upper stationary part, 12, through line, 20, to condenser coil, 21, and thence to receiver, 22. If desired, the valve, 23, may be interposed in the line, 20. The oil is subjected to surface distillation in the shell, 3, by means of a pair of burners, 24, arranged at opposite sides of the upper part of the shell, 3, and extending longitudinally alongside of the latter as shown at 25. The inner faces of the burner, 24, are slotted to distribute the heat equally over the entire length of the still or shell, 3. These burners, 24, are arranged at or above the liquid level in the shell, 3, so as to primarily heat the upper surface of the oil charge and produce surface distillation, thus preventing foaming of the emulsified oil in the still. The upper shell member, 4, is heated by similar burners, extending along opposite sides of the shell member, 4, the arrangement being such as to superheat the vapors in this shell member, 4.

It is also to be noted that the shell members are independently heated. It is, therefore, possible to heat the emulsified oil in the lower shell member at a temperature sufficient to dehydrate the oil and gradually fractionally distill the vapors while at the same time maintaining the temperature sufficiently low to prevent undue heating of the emulsified oil which would cause foaming. By independently heating the upper still member, the vapors themselves can be superheated to such a temperature as to produce substantial cracking of the oil vapors thereof. For example, if the process is carried out at atmospheric pressure the oil in the lower still member might be subjected to surface distillation at a temperature of from 450° F. to 750° F., while the vapors in the upper still member might be heated at a temperature of 800° F. to 1200°.

We claim as our invention:

1. In an apparatus for treating oil, the combination with a pair of superimposed

longitudinally extending still members, means for heating the upper portion of the lower still member so as to produce surface distillation of the contents thereof, means for superheating the vapors in the upper still member, and means for rotating said still members.

2. In an apparatus for treating oil, the combination with a pair of superimposed still members, means for introducing oil to the lower member, means for heating the upper portion of the lower still member so as to produce surface distillation of the contents thereof, means for delivering vapors from the lower to the upper member, means for superheating the vapors in the upper still member, and means for rotating said still members.

3. An apparatus for treating oil, comprising a rotating distilling member, means for feeding oil thereto, means for applying heat to said member to produce surface distillation of the oil therein, a rotating vapor chamber adjacent said still, communications between the still and the vapor chamber for delivering vapors from said still to the vapor chamber, means for simultaneously rotating the still and the vapor chamber, means for applying heat to the vapor chamber.

4. An apparatus for treating oil, comprising a rotating distilling member, means for feeding oil thereto, means for applying heat to said member to produce surface distillation of the oil therein, a rotating vapor chamber adjacent said still, communications between the still and the vapor chamber for delivering vapors from said still to the vapor chamber, means for simultaneously rotating the still and the vapor chamber, means for applying heat to the vapor chamber, a vapor outlet from said chamber and a condenser in communication therewith.

5. An apparatus of the character described, comprising a pair of rotating chambers, means for introducing oil to one of said chambers, means for heating the chamber to which the oil is introduced so as to produce surface distillation of the contents thereof, said means comprising an elongated heating device located adjacent the side of said chamber, means for delivering vapors from said last mentioned chamber to the other chamber, and means for heating the vapors while in said other chamber, means for rotating both of said chambers simultaneously, and a vapor discharge in communication with a condenser from said other chamber.

6. An apparatus for treating oil, comprising a pair of still members, means for introducing oil to one of said still members, means for heating said still member so as to produce surface distillation of the oil therein, means for delivering vapors from said still member to the second still member, means for rotating both of said still members, and

means for discharging vapors from said second still member.

7. An apparatus for treating oil, comprising a pair of still members, means for introducing oil to one of said still members, means for heating said still member so as to produce surface distillation of the oil therein, means for delivering vapors from said still member to the second still member, means for rotating both of said still members, means for heating the vapors in the second still member, and means for discharging the vapors therefrom.

8. An apparatus for treating oil, comprising a pair of rotating receptacles, means for delivering oil to one of said receptacles, means for heating the upper portion of said receptacle to produce surface distillation of the contents thereof, communications between said receptacle and said second receptacle, means for superheating the vapors in the second receptacle, means for discharging vapors therefrom, and means for rotating said receptacles.

9. An apparatus for treating oil, comprising a pair of rotating receptacles, means for delivering oil to one of said receptacles, means for heating the upper portion of said receptacle to produce surface distillation of the contents thereof, communications between said receptacle and said second receptacle, means for superheating the vapors in the second receptacle, means for discharging vapors therefrom, and means for rotating said receptacles, said heating means for each of said receptacles comprising elongated burners extending adjacent the sides of the receptacles.
